DESIGN FOR A REED FOR A MUSICAL INSTRUMENT

Andrew A. Verville, Nanuet, N. Y.

Application January 7, 1939, Serial No. 82,226

Term of patent 14 years

To all whom it may concern:

Be it known that I, Andrew A. Verville, a citizen of the United States, residing in Nanuet, county of Rockland and State of New York, have invented a new, original, and ornamental Design for a Reed for a Musical Instrument, of which the following is a specification, reference being had to the accompanying drawing, forming part thereof, in which:

Figure 1 is a top plan view of the reed for a musical instrument, showing my design;

Figure 2 is an edge elevational view; and
Figure 3 is an end elevational view thereof.

I claim:

The ornamental design for a reed for a musical instrument, as shown.

ANDREW A. VERVILLE,
